WESTERN ELECTRIC COMPANY, INCORPORATED, A CORPORATION OF NEW YORK.

ELECTRICAL CONTROLLING SYSTEM.

1,183,890.

Specification of Letters Patent. Patented May 23, 1916.

Application filed November 2, 1914. Serial No. 869,804.

To all whom it may concern:

Be it known that I, ALBEN E. LUNDELL, a citizen of the United States, residing at New York city, in the county of New York and State of New York, have invented certain new and useful Improvements in Electrical Controlling Systems, of which the following is a full, clear, concise, and exact description.

10 This invention relates to electrical controlling systems, and more particularly to a two-wire interoffice trunking system for telephone exchanges. Its object, as applied to a telephone system, is to provide for the proper performance of telephonic and various signaling and switch-operating functions by means of controlling circuits extending over the two wires of each trunk.

In the system herein disclosed to illustrate 20 the preferred embodiment of the invention, there is provided a supervisory signal and means for controlling it over a signaling circuit extending through one of the two trunk wires, also an automatic ringing mechanism, with means for controlling its 25 operation over a second signaling circuit extending over the other of the two trunk wires, for the purpose of reringing on the called subscriber's line. In combination 30 with these there is further provided a switch restoring magnet with means to operate it under the joint control of both of the signaling circuits. The two signaling circuits are 35 preferably closed during the time the trunk is in use as a telephonic link between subscriber's stations. Under this condition of the apparatus the supervisory signal located, say at an operator's position at the end of the trunk nearest the calling line, is operated 40 by opening one of the signaling circuits at the switch end of the trunk. The automatic ringing mechanism which preferably is initially operated by means local to the switch end of the trunk, can thereafter have 45 its active condition reestablished to "re-ring" by opening momentarily the other signaling circuit at the operator's end of the trunk; and finally the switch restoring magnet may be operated by simultaneously 50 opening both signaling circuits at the operator's end of the trunk.

Referring to the drawing, the complete equipment and circuits of a telephone exchange system necessary for the establishment of connections selectively between

various subscribers' lines, not being necessary to a full understanding of the invention, are not shown. There are numerous well-known mechanisms for this purpose. It is sufficient to assume that connections 60 have been established through several line and trunk switches, the exact number and kind of which may be varied without departing from the invention. As the system of circuits is shown the bell at the called station has not yet been rung, and the called subscriber has not yet lifted his receiving telephone. The various switches used for establishing the connection between the subscribers' lines may be manual or automatic, 65 but it is contemplated that the switch which joins the trunk to the called line preferably is of some automatic type, the restoring of which, to effect disconnection of the called line from the trunk, may be controlled from 70 the distant end of the trunk. In the description the reference character G (not shown in the drawings) is used to designate ground connections.

Two subscribers' stations 1 and 2 are 80 shown connected by way of contacts 3, 4 of a spring-jack and plug-switch 5, contacts 6, 7 of an automatic switch, two wires 8, 9 of a two-wire interoffice trunk and contacts 10, 11 of another automatic switch. The 85 connecting link between the contacts 3, 4 and 6, 7 may be divided, as usual, by repeating coil windings 12, 13 and 14, 15 into inductive sections, and the trunk likewise by repeating coil windings 16, 17 and 18, 19. 90 Current is supplied to the calling line and to the trunk by a battery B 20, and to the called line by a battery B 21. A condenser 22, intermediate the windings 16, 17, makes the calling line section of the trunk a closed 95 telephonic link.

An automatic ringing mechanism, which may be of any desired construction, comprises, as shown, three relays 23, 24 and 25, a ringing generator 26, and a starting switch 100 27. The closure of the starting switch may be caused, as in automatic systems, to follow immediately after the establishment of a connection with and test of a wanted idle line. When thus, or in any other manner, 105 this switch is closed, a local circuit G (ground), 27, 28, 29, 23, 30, 31, 32, 33, B 21 (battery) is established. This causes ringing relay 23 to act, opening at contacts 34, 35 the trunk line section leading to the called 110

line, and closing the ringing circuit—26, 24, 36, 82, 11, 2, 10, 81, 37, G—ringing the substation bell. When the subscriber responds, this circuit receives an increase of current, 5 and the relay 24 acts, opening at contact 28 a shunt about relay 25. Relay 25 in turn acts, opening at 29 another contact in this shunt, and closing at contact 38 a shunt about relay 23 which reacts, disconnecting 10 the ringing generator from the line and establishing the battery circuit to the called line. A supervisory relay 39 now acts, closing at contact 40 a signaling circuit over wire 9 of the two-wire trunk, as follows: 15 B 20, 15, 41, 42, 7, 9, 43, 44, 17, 45, 46, 40, G. This circuit includes several contacts, the function of which will be stated hereinafter, an impedance coil 45 which avoids a direct ground connection to the telephonic link, 20 and a supervisory relay 41 which acts to shunt a supervisory lamp signal 47. This supervisory signal is now under the control of the called subscriber, who may flash it repeatedly by opening and closing his line. 25 Assume that the called subscriber responds and then replaces his receiver. The signal lamp 47 becomes lighted and if the other supervisory signal 48 is also lighted, indicating that the calling subscriber has also 30 replaced his receiver, then the operator would proceed to disconnect the lines. But if for any reason it is desired to rering the called party, the operator may reestablish the active condition of the ringing mechanism by momentarily depressing the "rering" key 49. Prior to this, there had existed a closed signaling circuit through the trunk wire 8, as follows: B 21, 50, 51, 52, 53, 16, 8, 6, 54, 55, 14, G; also a second local 35 circuit: G, 56, 57, 31, 32, 33, B 21; and a third local circuit: G, 58, 59, 60, 61, B 21. The depression of the rering key, which opens contact 55, causes the relay 53 to react, opening at contact 32 the local ringing 40 and the second local circuits. Relay 25 opens the shunt about relay 23 and recloses the shunt about itself. Relay 57 also reacts, opening at 46 a contact in the supervisory signaling circuit, closing at 62 a connection 45 for relay 59 to wire 9 of the trunk, and opening at 60 a contact in the third local circuit. Contact 62 makes before contact 60 breaks, so that relay 59 will remain energized provided it finds a substitute path for 50 battery current over the trunk wire 9, which it does under the present assumption, the circuit being as follows: G, 58, 59, 62, 63, 43, 9, 7, 42, 41, 15, B 20. As the rering key is 55 momentarily depressed, the original signaling circuit over the trunk wire 8 becomes closed again, and relay 53 acts to reclose the original local ringing circuit, causing the ringing relay 23 to again apply ringing current to the called line. If and when the subscriber again responds, relays 24, 25 and 23

act as before, cutting off the ringing current. The operation of rering may be repeated as often as required.

Assume now that the lines are ready to be discontinued. This, in the semi-automatic system disclosed, is a condition usually brought about by both parties having replaced their receivers, and both supervisory signals 47 and 48 being displayed. Various means may be employed at the calling 75 line end of the trunk for starting the disconnect. As shown the operator starts it by removing the plug from the spring-jack of the calling line. This breaks a local circuit which included a cord relay 64 and a 80 cut-off relay 65. The former reacts, opening at 66 a contact in the calling line supervisory signal circuit, and closing at 67 a circuit for relay 68, which in turn closes at contact 85 the motor magnet circuit of a 85 sequence switch 69. The function of the sequence switch is to control various circuits in a particular manner, and thus to bring about a desired sequence of operations. At the time of the closure of the last-mentioned 90 circuit, the sequence switch 69 was resting in "talking" position, say position 16, and it is now moved to the "switch return" position 18, wherein there is closed at contact 70 a circuit for the restoring magnet 71, the 95 function of which is to return to normal the automatic switch which had previously established the connections at contacts 6 and 7 between the connecting link and trunk. In its movement from position 16 to 18 the 100 sequence switch 69 opened contacts 72, 73, 74 and 75 in various local circuits, and contacts 54 and 42 in the trunk signaling circuits. Thereupon relays 53, 25 and 57 react as before, and relay 59 is again connected at contact 105 62 to the trunk wire 9. In this instance, however, the path for battery current is open at contact 42 so that relay 59 is not maintained energized, but reacts opening at 51 a contact in the signaling circuit over wire 110 8, and closing at contact 76 the motor magnet circuit of a sequence switch 77. This sequence switch, like 69, had been resting in talking position, say 16, and it is now advanced to the return position 18, wherein at contact 78 there is closed the circuit of a restoring magnet 79, the function of which is to return to normal the automatic switch, which had previously established the connections at contacts 10 and 11 between the 115 trunk and the called line. In its movement from position 16 to 18, the sequence switch 77 opened contacts 50, 58, 80, 52, 30, 31, 33 and 56 in various local circuits, contacts 43, 44 and 63 in the circuits of wire 9, and contacts 81 and 82 in the circuit to the called line. Master contacts 83 and 84 are closed between the various resting positions of the 120 sequence switches.

In brief, the operation is as follows: To 130

ring initially the starting switch 27 is closed, whereupon ringing relay 23 acts to connect the generator 26 to the wanted line. When the called subscriber responds, relays 24 and 5 25 act and relay 23 reacts, cutting off the ringing current. The called subscriber now has control of the supervisory signal 47 by means of relay 39 in the circuit of his line. This relay reacts when he replaces his receiver, opening the signaling circuit over wire 9, causing supervisory relay 41 to react and the signal 47 to be displayed. To ringing the operator momentarily depresses key 49, which causes relays 53, 25 and 57 to react, relay 59, however, remaining energized by reason of its connection through contact 62 to the closed trunk wire 9. Upon the release of key 49, the signaling circuit over wire 8 is reclosed, and the ringing relay 23 10 acts as before to connect generator to the line. To disconnect the signaling circuits of both trunk wires 8 and 9 are opened at contacts 54 and 42, following, as in the system disclosed, the removal of the plug from 15 the spring-jack of the calling line. Relays 53, 25 and 57 react, as in the case of reringing, and relay 59 also reacts because it does not find a path for current over the now open trunk wire 9. The reaction of relay 59 causes the energization of the switch-restoring magnet 78.

In the particular system described it will be noted that two of the controlled devices, namely the automatic ringing relay 23 and 35 the switch restoring magnet 79 are both dependent for their operation in the first instance upon the actuation of switch operating mechanism comprising the relays 53 and 57, which respond, that is to say, react upon 40 the opening of the trunk circuit over wire 8 and that the operation of the one or the other of these two devices is thereupon selectively determined by the relay 59 which acts as a testing mechanism to determine the 45 closed or open condition of the trunk circuit over wire 9.

What is claimed is:

1. In a telephone trunking system, two wires joined to form a telephonic link and 50 separately forming controlling circuits, a supervisory signal under the control of one and ringing mechanism under the control of the other of said circuits, and a switch controlling device under the joint control of both 55 said circuits.

2. In an electrical controlling system, two wires joined to form a telephonic link and 60 separately forming signaling circuits, signaling devices one at each end of said link controlled over said circuits respectively, and a switch controlling device controlled over said circuits jointly.

3. In a telephone trunking system, two wires joined to form a telephonic link and 65 separately forming closed controlling cir-

cuits, a ringing device operable upon the opening of one of said circuits alone, and a switch controlling device operable upon the opening of both said circuits.

4. In a telephone trunking system, two 70 wires joined to form a telephonic link and separately forming controlling circuits, a supervisory signal under the control of one of said circuits, and a ringing device under the control of the other of said circuits. 75

5. In a telephone trunking system, two wires joined to form a telephonic link and separately forming independently operable closed signaling circuits, and a switch controlling device operable upon the opening 80 of both said circuits.

6. In an electrical controlling system, two wires extending parallelly between points and separately forming closed controlling circuits, a signaling device at one of said points controlled over one of said circuits, a signaling device at the other of said points controlled over the other of said circuits, and a switch controlling device at one of said points operable under the joint control of 90 both said circuits. 85

7. In an electrical controlling system, two wires extending between two points and separately forming closed controlling circuits, a signaling device at one of said points, 95 means for operating said device upon the momentary opening of one of said circuits at the other of said points, a second signaling device at said other point, means for operating said second signaling device upon the opening of the other of said circuits at the first mentioned point, a switch-controlling magnet at the first mentioned point, and means for operating said magnet upon the opening of both said circuits at the said 100 other points. 105

8. In a telephone trunking system, two wires extending parallelly between two points and separately forming closed controlling circuits, a ringing device at one point, means for operating said device upon the momentary opening of one of said circuits at the other point, a supervisory signal at said other point, means for operating said signal by opening the other of said circuits at the first mentioned point, a switch-controlling magnet at the first mentioned point, and means for operating said magnet by opening both said circuits at the said other point. 110 115

9. In a telephone exchange system, the combination with a two-wire trunk, a called subscriber's line, a switch connecting said trunk and line, a restoring device for said switch, and automatic ringing mechanism associated with said switch, of means also associated with said switch for rendering the ringing mechanism active, means controlled over one wire of the trunk for re-establishing the active condition of the ring- 125 130

- ing mechanism, and means controlled over both wires of the trunk jointly for operating said restoring device.
10. In a telephone exchange system, the combination with a two-wire trunk, a called subscriber's line, a switch connecting said trunk and line, a restoring device for said switch, ringing mechanism associated with the ringing mechanism associated with the switch end of the trunk, and a supervisory signal associated with the other end of the trunk, of means controlled over the subscriber's line and one wire of the trunk for operating the supervisory signal, means controlled over the other wire of the trunk for operating said ringing mechanism, and means controlled over both wires of the trunk for operating said restoring device.
11. In a telephone exchange system, the combination with a two-wire trunk, a called subscriber's line, a switch connecting said trunk and line, a restoring device for said switch, ringing mechanism associated with the switch end of the trunk, and a supervisory signal, of means controlled over the subscriber's line and said trunk for operating the supervisory signal, means controlled over said mechanism, and means also controlled over said trunk for operating said restoring device.
12. In a telephone exchange system, the combination with a two-wire trunk, a called subscriber's line, a switch connecting said trunk and line, automatic ringing mechanism associated with the switch end of the trunk, and a supervisory signal associated with the other end of the trunk, of means local to the switch end of the trunk for rendering said ringing mechanism active, means controlled over the subscriber's line for rendering the ringing mechanism inactive, means controlled over said trunk for re-establishing the active condition of the ringing mechanism, and means controlled over the subscriber's line and said trunk for operating the said supervisory signal.
13. In a telephone exchange system, two wires joining to form a telephonic trunk and each forming an independent controlling circuit, a signaling device at one end of said trunk, a second signaling device and a switch-controlling magnet at the other end of said trunk, a switch at the last mentioned end of the trunk adapted to open one of the controlling circuits to operate the first mentioned signaling device, a switch at the first mentioned end of the trunk adapted to open the other controlling circuit to operate the second signaling device, a switch at the said first mentioned end

of the trunk adapted to open the first mentioned controlling circuit, and means controlled by the joint opening of both controlling circuits at the said first mentioned end of the trunk for operating said switch-controlling magnet.

14. An electrical controlling system, comprising two devices at one point to be controlled from a distant point, a third device at the distant point to be controlled from the first mentioned point, two wires extending between said points and each forming a closed controlling circuit, means for operating one of the first mentioned devices by momentarily opening one of said controlling circuits, means for operating the said third device by opening the other of said controlling circuits, and means for operating the other of the said first mentioned devices by opening both said controlling circuits.

15. A controlling system comprising two devices at one point to be controlled from a distant point, two closed circuits extending between said points, means at the distant point for opening one or both of said circuits at will, switch operating mechanism at the first mentioned point responsive to the opening of one of said circuits, a testing mechanism adapted upon the actuation of said switch operating mechanism when said circuit is opened to test the condition of the other circuit, the operation of the two devices both being dependent upon the actuation of said switch operating mechanism but selectively determined by said testing mechanism.

16. In a telephone exchange, the combination with a system of circuits between lines including a two-wire trunk, and an automatic ringing apparatus and a switch restoring device at the incoming end and a supervisory signaling device at the outgoing end of said trunk, of means controlled over said trunk for resorting the automatic ringing apparatus, means controlled over said trunk for operating said switch restoring device, and means controlled over said trunk for operating said supervisory signaling device, the control of said automatic ringing apparatus and said supervisory signaling device being effected without interference with the control of said switch restoring device.

In witness whereof, I hereunto subscribe my name this 29th day of October, A. D. 115 1914.

ALBEN E. LUNDELL.
